ELECTRIC SHAVER SHEAR PLATE AND
METHOD OF MANUFACTURE

Norman A. Gray, Stamford, Conn., assignor, by
mesne assignments, to Schick Incorporated, a
corporation of Delaware

Application November 3, 1944, Serial No. 561,683

12 Claims. (Cl. 76—104)

1

This invention relates to electric shavers of the kind in which the shearing head, or so much of it as constitutes the shear-plate proper and its adjoining side walls, is formed up from a sheet-metal blank; and, while not limited thereto, it has particular application to shear-plates of this type provided with so-called combing, in the nature of overhanging edge portions serving to pick up and facilitate the entry of hair into the hair-receiving openings in the shear-plate.

The primary object of the invention is a method of manufacture which results in a shear-plate combining maximum strength and shaving area while requiring a minimum of machining operations for its production.

With the above and other objects in view, as will hereinafter appear, the invention comprises the methods, devices, combinations and arrangements of parts hereinafter set forth and illustrated in the accompanying drawing of a preferred and a modified embodiment of the invention, from which the several features of the invention and the advantages attained thereby will be readily understood by those skilled in the art.

In the drawing, Figs. 1 and 2 are sectioned perspective views of a preferred form of the improved shearing head in different stages of manufacture, Fig. 3 is a similar view of a modified form, and Fig. 4 is a diagram illustrating certain of the forming operations incident to the manufacture of the shearing head.

In accordance with the present invention the shear-plate and its supporting walls are formed from a rectangular sheet metal blank pierced to provide suitable hair-receiving openings. Such a blank, marked 1, is indicated in section in Fig. 4. As there shown by the full-line outline, which represents the result of the first forming operation, the blank at this stage includes a central, curved portion 2, adjacent acute-angled portions 3 and recessed portions 4.

In the next forming operation the blank is bent up to substantially U-shaped form and given its ultimate general contour, as illustrated in dotted outline in Fig. 4. In this operation the above-mentioned central, curved portion has been bowed outwardly to form the shear-plate proper (generally designated 5 in Fig. 2) and the acute-angled portion 3 and recessed portions 4 assume their respective positions as the combing and supporting side walls on each side of the shear-plate.

Either coincidently with this bending operation, as by means of a compound die, or as a separate operation, a limited section of the central or shear-plate portion of the U is embossed to provide an outwardly projecting or raised panel 6, Fig. 1, running throughout the length of the head. The depth or extent of the embossing is such that the inner surface 7 of the embossed portion remains within the contour of the outer surfaces

8 of the adjacent, unembossed zones on either side of the panel 6. After the base block 9 has been inserted the head is at the stage illustrated in Fig. 1. As will be observed, the inner face of the shear-plate now comprises the central, raised surface 7 bordered by and merging abruptly into the surfaces 10.

The head is then mounted on a grinding arbor and the outer face of the shear-plate is ground to an extent to reduce it to the smooth contour shown in Fig. 2; that is, the raised portion of panel 6 is ground off, producing the uniformly thin, central shearing zone, marked 11 in Fig. 2, bordered by the thicker, supporting zones 12. If need be the grinding may, of course, be continued into the zones 12 to the extent necessary to reduce the central shearing zone 11 to the thinness required. However, a limited portion 13 of panel 6, at each end of the head, is preferably left intact, to provide a suitable reinforcement. Except for finishing operations the head is then complete.

As above stated, the blank 1 from which the shear-plate and walls are formed is suitably pierced. In this form, and preferably, the piercing takes the form of slots and so arranged as to provide a central row of hair-receiving openings 14 wholly within the thin, central shearing zone. On each side, and staggered in relation to slots 14, are slots 15 which extend through the side walls 4, the combing 3 and into the thin, central zone. Thus a suitable inner cutter (not shown) bearing against and within the lateral limits of the nether surface of the thin shearing zone can cooperate both with the central slots 14, throughout their length, and with the inner ends of the slots 15.

Not only are the necessary machining operations reduced to a minimum by the described method of manufacture, but also the resulting form of the shear-plate provides certain very definite advantages. The thickness of the side walls, providing maximum strength, continues through the combing and marginal shear-plate zones clear up to the central or shaving zone; and the latter, in turn, can be made uniformly extremely thin over a relatively wide area. Heretofore, as is well known, a common practice has been to grind the inner and outer surfaces of the shear-plate to taper the thickness outwardly from a thin central portion to thicker side portions, achieving the necessary strength at the sides at the sacrifice of width of the thin central zone and introducing intermediate zones of varying thickness greater than the minimum at the center and incapable of cutting as closely.

The shearing head illustrated in Fig. 3 differs from that shown in Figs. 1 and 2 only in the shape of the shear-plate, which is flat instead of curved. The method of manufacture is the same. The initial blank can be identical with that already

described; and in the bending or second forming operation it is necessary only to change the central portion of the die to convert the central, curved portion 2 of the blank to flat rather than outwardly curved form. As in the Fig. 2 form, the described embossing and grinding produces a thin, central, shearing zone 16 merging abruptly into thicker, marginal zones 17. The arrangement of the slots can also be the same as already described and the ends of the head reinforced, as before, by refraining from grinding down the portions 18.

In the light of the foregoing description the following is claimed:

1. A sheet metal shear-plate formed to provide a face-contacting zone having a smooth, convex, outer surface and a stepped inner surface forming, with the outer surface, a thin central portion merging abruptly into thicker marginal portions, inwardly bent wall portions forming acute-angled combs, hair-receiving openings in the thin central portion, and hair-receiving slots extending through the combs and thicker marginal portions and into the thin central portion.

2. A sheet metal shear plate formed to provide a face-contacting zone bordered by downwardly extending converging walls forming acute-angled combing portions at the edges of the face-contacting zone, said face-contacting zone presenting a smooth surface and the underside of the shear-plate spaced therefrom to provide a uniformly thin central section abruptly merging into relatively thick sections continuing into and through the combing portions.

3. A sheet metal shear-plate having a smooth, convex, outer surface, a uniformly thin central zone merging abruptly into uniformly thin but substantially thicker marginal zones, and hair-receiving openings in the said central zone and in the said marginal zones.

4. A shear-plate having a smooth convex outer surface, and an inner surface spaced from the outer surface to provide a uniformly thin central section abruptly merging into relatively thick marginal sections.

5. In the manufacture of electric shaver shear-plates, the method which includes the steps of forming a sheet metal blank into a substantially U-shaped member, embossing a limited central portion only of the U to project such portion outwardly to an extent such that the inner surface of the embossed portion remains within the contour of the outer surfaces of the adjacent unembossed portions, and grinding down the outwardly projected portion throughout at least part of its length to a depth to bring the outer surface thereof into conformity with the contour of the said outer surfaces of the adjacent unembossed portions and into parallelism with the said inner surface of the embossed portion, thereby producing a uniformly thin central portion merging into relatively thick marginal portions.

6. In the manufacture of electric shaver shear-plates, the method which includes the steps of forming a sheet metal blank into a substantially U-shaped member, embossing a limited central portion only of the U to project such portion outwardly to an extent such that the inner surface of the embossed portion remains within the contour of the outer surfaces of the adjacent unembossed portions, and grinding down the outwardly projected portion throughout at least part of its length to a depth to bring the outer surface thereof into conformity with the contour of the said

outer surfaces of the adjacent unembossed portions.

7. In the manufacture of electric shaver shear-plates, the method which includes the forming of a pierced, sheet metal blank into a substantially U-shaped member, and, coincidently, embossing a limited central portion only of the bridge portion of the U to provide outer marginal surfaces on each side of an abruptly raised surface.

8. A sheet metal shear-plate formed to provide a face-contacting zone bordered by converging walls forming acute-angled combing portions, the face-contacting zone having a smooth outer surface and a stepped inner surface forming, with the outer surface, a uniformly thin central portion merging abruptly into thicker marginal portions, spaced hair-receiving openings in the uniformly thin central portion, and hair-receiving slots, staggered with respect to said openings, extending through the combing portions and thicker marginal portions and into the uniformly thin central portion.

9. A sheet metal shear-plate formed to provide a face-contacting zone bordered by converging walls forming acute-angled combing portions, the face-contacting zone having a smooth outer surface and a stepped inner surface forming, with the outer surface, a uniformly thin central portion merging abruptly into thicker marginal portions, and hair-receiving slots, closed at their inner ends, extending through the combing portions and thicker marginal portions and into the uniformly thin central portion.

10. A shear-plate having a smooth convex outer surface, and an inner surface spaced from the outer surface to provide a uniformly thin central section abruptly merging into relatively thick marginal sections, said shear-plate having hair-receiving slots extending through the said marginal portions and into, and terminating in the said uniformly thin central section.

11. A shear-plate having a smooth flat outer surface, and an inner surface spaced from the outer surface to provide a uniformly thin central section abruptly merging into relatively thick marginal sections, said shear-plate having hair-receiving slots extending through the said marginal portions and into, and terminating in the said uniformly thin central section.

12. In the manufacture of electric shaver shear-plates, the method which includes the steps of forming a sheet metal blank into a substantially U-shaped member, embossing a limited central portion only of the bridge portion of the U to project such portion outwardly with respect to the contiguous surfaces of the balance of the bridge portion of the U, and grinding material off the outer surface of the embossed portion to produce a uniformly thin central portion merging abruptly into relatively thick marginal portions.
